UNITED STATES PATENT OFFICE.

JAMES A. GIESE, OF CHICAGO, ILLINOIS, ASSIGNOR TO THE ADAMS & WESTLAKE COMPANY, A CORPORATION OF ILLINOIS.

WINDOW-STOP.

1,178,580.

Specification of Letters Patent. Patented Apr. 11, 1916.

Application filed July 30, 1915. Serial No. 42,810.

To all whom it may concern:

Be it known that I, JAMES A. GIESE, a citizen of the United States, and resident of Chicago, county of Cook, and State of Illinois, have invented certain new and useful Improvements in Window-Stops, of which the following is a specification, and which are illustrated in the accompanying drawings, forming a part thereof.

10 The invention relates to stops for windows; its object being to provide a construction in which the stop is moved toward the sash by the weight thereof, when engaged by a locking bolt, thereby forcing the sash 15 against the opposing stop and insuring a tight joint.

The invention consists in a structure such as hereinafter described, and is illustrated in the accompanying drawings, in which—

20 Figure 1 is an inside elevation of a window to which the improved stop is applied; Fig. 2 is a sectional view on the line 2—2 of Fig. 1; Fig. 3 is a detail view in perspective of the stop removed from the window casing; Fig. 4 is a face view of the stop; partly in section; Fig. 5 is a similar view entirely in elevation; and Figs. 6, 7 and 8 are detail sections on the lines 6—6, 7—7 and 8—8, respectively, of Fig. 4.

30 A window casing is represented at 10, and a sash fitted thereto at 11, both being of ordinary construction. The sash is shown as provided with a pair of latches 12, 13, of any desired form, comprising a reciprocating bolt 14. The outer stop 15, against which the sash 11 bears, may be of any preferred form, preferably stationary, and there is shown a common rectangular parting strip for this purpose.

40 The improved stop is applied to the inner face of the sash and comprises a plate 16, secured to the inner face of the stile member of the window casing. As shown, this plate is provided with a pair of parallel longitudinal flanges 17, 18, which provide a runway for a window curtain. This feature, however, forms no part of the present invention. To the face of the plate 16 there is applied a movable stop member 19, having 50 the general form of a channel bar, the channel facing toward the plate 16 and the inner side face of the bar being adapted to bear against the face of the sash. This bar 19 is vertically and laterally movable, and is held

in place by lugs 20 (three being shown), 55 which are fixed to the plate 16 and project into slots 21 formed in the inner side or flange of the bar 19. Cams are provided for moving the bar 19 laterally as it is moved vertically. For this purpose there is shown 60 a plurality of plates 22, 23 and 24,—as many being employed as may be deemed advisable. Each of these plates is provided near its lower end with a beveled face 25, with its edge remote from the sash, the inclination 65 of this face being upwardly away from the sash. Each of these plates is provided near its upper end, and on its edge adjacent the sash, with a similarly inclined face 26.

70 Cam surfaces 27, 28, are provided on the inner faces of the side flanges of the bar 19, both being inclined upwardly away from the sash and so positioned as to coöperate with the beveled faces 25, 26, of the plates 22, 23, 24. The vertical movement of the 75 bar 19 is determined by the length of the slots 21. When the bar is in its upper position, as shown in Fig. 4, it is cammed backwardly away from the sash by the coöperative action of the inclines 25, 27. When it 80 is lowered it is cammed toward the sash by the coöperative action of the inclines 26, 28. If desired a spring 29 may be provided for holding the bar 19 in its upper position.

85 Apertures 30, 31, 32, 33, as many as may be deemed advisable, are formed in the web portion of the bar 19 for receiving the latch bolt 14. When the bolt enters one of these apertures the weight of the sash will draw the bar 19 downwardly, and the lateral 90 movement of this bar will force the sash snugly against the opposing stop 15. A lug 34 is preferably formed on the face of the web portion of the bar 19, at the lower end of the bottom bolt-receiving aperture 30, insuring the downward movement of the bar and bringing the aperture 30 in alinement with the bolt when the sash is in its lowest position. For the purpose of reinforcement of the bottom walls of the apertures 31, 32 100 and 33, fixed supports 35, 36 and 37 are preferably attached to the plate 16, and so positioned as to form a bearing for the latch bolt when entered therein, the bar 19 having been moved to its lower position.

105 In practice the spring 29 may be dispensed with in many instances with advantage, the friction between the sash and the

bar 19 preventing the sash from descending rapidly when the latching bolts are withdrawn.

It will be understood that the improved 5 stop is preferably applied at both sides of the window casing. A stop 38 is formed on the bar 19 in position to be engaged by the upper face of the locking bolt when the latter enters and passes through the aperture 10 30, firmly holding the sash in closed position.

Various changes in details of construction 15 may be made without departing from the scope of the invention. The construction shown and described is durable and operates satisfactorily, both with and without the 20 spring.

The device tends to firmly hold the sash against the opposing or fixed stop throughout its entire vertical length, insuring complete 25 exclusion of the weather and effectively preventing settling of the sash when in any of its positions.

I claim as my invention—

1. In a window stop, in combination, a 25 plate adapted for attachment to the side member of a window casing, a series of vertically arranged cam elements each having oblique faces on their sides adjacent the runway for a sash, such faces being inclined 30 downwardly toward such runway and oblique faces on their opposite sides inclined upwardly and away from such runway, a channel bar inclosing such cams and having bearings engaging both sets of such oblique cam faces, such bar being apertured to receive a sash bolt.

2. In a window stop, in combination, a 35 plate adapted for attachment to the side

member of a window casing, a series of vertically arranged cam elements each having 40 oblique faces on their sides adjacent the runway for a sash inclined downwardly toward such runway, and oblique faces on their opposite sides inclined upwardly and away from such runway, a channel bar inclosing 45 such cams and having bearings engaging both sets of such oblique cam faces, such bar being apertured to receive a sash bolt, and having an outstanding bolt engaging lug at the lower margin of the lowest bolt receiving 50 aperture.

3. In a window stop, in combination, a stationary member, a sliding member carried thereby and having a bolt aperture, a lug on the sliding member at the bottom of 55 the bolt aperture, and a bolt-engaging lug on the stationary member at the upper end of the bolt aperture when the sliding member is at its lower position.

4. In a window stop, in combination, a 60 stationary member, a vertically and laterally movable member mounted thereon, such two members being engageable by a sash bolt when the sash associated with the stop is in its lowest position.

5. In a window stop, in combination, a stationary member, and a vertically and laterally movable member carried thereby, the movable member being adapted to be moved downwardly and toward the sash associated with the stop by the closing of the sash, and the stationary member being engageable by a sash bolt when the sash is in its 70 closed position.

JAMES A. GIESE.
